UNITED STATES PATENT OFFICE

2,495,256

ROTARY BOILER HAND-HOLE
SEAT SCRAPER

Omar F. Hoelzel, Portsmouth, Va.

Application July 19, 1946, Serial No. 684,904

4 Claims. (Cl. 15—104.02)

(Granted under the act of March 3, 1883, as
amended April 30, 1928; 370 O. G. 757)

1

This invention relates to a rotary power-driven scraper. In particular, the invention relates to a power-driven rotary scraper which is hollow and frusto-conical in shape.

The general object of the invention is to provide a rotary, power-driven scraper which is adapted to clean the contact surfaces of closures such as the hand-hole seat in the headers of boilers.

It is also an object of this invention to provide a rotary, metallic, power-driven scraper which is composed of metal softer than that of the hand-hole seat whereby there is no scoring action on the seat by the operation of the scraper.

It is an additional object of this invention to provide a scraper which will remove all foreign material such as rust, and compacted water sediment from the seat, thereby leaving no humps of rust or sediment which cause the hand-hole cover to be cocked when "dogged" into position and have a deleterious effect on the gasket.

It is a further object of this invention to provide a rotary, power-driven scraper, which is frusto-conical in shape and which constitutes an efficient scraping tool for the removal of foreign material from the seats of hand hole covers in boilers and headers.

It is a still further object of this invention to provide a rotary power driven scraper which is readily manipulated and which is of sturdy construction and capable of economical manufacture.

These and other objects of the invention will appear more fully from the following description, the herewith appended claims and in the accompanying drawing in which,

Figure 1 is a top elevational view of the scraper,

Figure 2 is a side elevational view of the same,

Figure 3 is a vertical sectional view taken along section line 3—3 of Figure 2. It is partly in section and partly in elevation, and

Figure 4 is a sectional, elevational view showing the scraper of this invention in operative position on the hand-hole seat in a boiler header.

Figures 1, 2 and 3 are self-explanatory. They are submitted for clarity of disclosure.

In Figure 4 the scraper and driving assembly is shown generally at 10 in operative relationship to handhole seat 12 which is positioned in boiler header 14. The lower edge 16 of scraper 11 is the scraping and cutting edge which by rotary and firm contact with the handhole seat removes the foreign matter such as rust and compacted water sediment from the seat. Scraper 11 is frusto-conical in shape. It is hollow, being open at the

2

larger end and closed by integral plate 18 at its smaller end. Plate 18 is provided with a centrally positioned opening 19 through which a threaded portion 20 of shaft 21 projects. This threaded portion 20 is of smaller diameter than shaft 21, thereby providing a shoulder 22 on the said shaft which functions as an abutment against which washer 24 rests. In assembling the scraper on the driving shaft 21 as herein shown, washer 24 is placed on shoulder 22, scraper 11 is then positioned with plate 18 resting on washer 24, washer 26 is then immediately placed beyond plate 11 and the whole assembly is held firmly in position by nut 28. Shaft 21 extends beyond scraping edge 16 and may be driven by any suitable source of power such as a portable air driven motor 30.

In use, the rotary scraper is manipulated by grasping the portable motor 30 and directing the scraping edge 16 against hand-hole seat 12 in boiler header 14 and working the scraper 11 and portable motor 30 around the hand-hole seat 12 as a unit, holding the scraper edge 16 firmly in interior corner 13. In this manner the foreign matter on the seat is quickly and thoroughly removed. It will be obvious that the softer material of the conical body will be worn away by rubbing contact with the harder metal of the surface being cleaned, and that the base of the conical scraper is thereby continually renewed and the edge thereof sharpened as the scraper walls are shortened by wear. The foreign material removed is primarily of material softer than the scraper material, which may be of alloy copper, brass, soft steel, or the like, such that the foreign material is cut thereby. It is preferred that the conical base of the scraper be approximately tangent to the surface being cleaned in order that the included angle between the base and the cone elements be somewhat less than ninety degrees, as illustrated, since the cleaning action is facilitated by the lifting and shearing action resulting therefrom.

While the foregoing description has been drawn to the application of a rotary, power-driven conically shaped scraper to the cleaning of a boiler header hand-hole seat, it is not desired to be strictly limited thereto, since this type of scraper can be used in cleaning other types of seats and metallic surfaces. Such other applications and uses are included within the scope of the invention to the extent as defined by the herewith appended claims.

The invention described herein may be manufactured and used by or for the Government of

the United States of America for governmental purposes without the payment of any royalties thereon or therefor.

I claim:

1. A rotary, power-driven scraper adapted to remove foreign material from metallic surfaces comprising a hollow, thin-walled, frusto-conically shaped body composed of metal softer than that of the metallic surfaces and harder than said material, the said body being provided with a closed small end and an open large end, a portable shaft extending concentrically through the large end of the body, means for locking the end of the shaft concentrically to the closed end of the body and means for rotating the body in contact with the surface while the shaft intersects the plane of said surface at substantially ninety degrees thereto, said body being continuously sharpened at the larger conical edge by said rotation against said surface. 5 10 15 20

2. A rotary, power-driven scraper adapted to remove foreign material from metallic surfaces comprising a hollow, frusto-conically shaped body composed of metal softer than that of the metallic surfaces and provided with a small end and an open large end; a shaft extending through the large end of the body, means for securing the shaft concentrically to the body and means for rotating the shaft and body with the conical base of the body in substantially flat engagement with said surfaces, the peripheral conical edge thereof being a rotative cutting edge; said rotation continually sharpening said edge by rubbing contact with said surfaces.

3. A rotary, power-driven scraper adapted to remove foreign material from metallic surfaces comprising a hollow thin-walled, conical body composed of softer metal than that of the metallic surfaces and provided with a small end and an open large end having a peripheral edge, a shaft extending concentrically through the body

to the small end thereof, means for securing the shaft to the body and means for rotating the shaft and body with said peripheral edge in scraping contact with the metallic surfaces, said scraping contact continually renewing the peripheral edge of the body as the thin wall thereof wears away.

4. A rotary, power-driven scraper adapted to remove foreign material from metallic surfaces comprising a thin-walled, tapered hollow body composed of metal softer than that of the metallic surfaces, the said body being provided with a closed small end and an open large end, the largest diameter thereof forming a circular cutting edge, a portable shaft extending through the large end of the body, means for locking the end of the shaft to the closed end of the body and means for holding and rotating the portable shaft and body with said open large end in substantially flat scraping contact with said surfaces, said scraping contact continually sharpening said edge.

OMAR F. HOELZEL.
